OTTO J. HERMANN, OF LAKESIDE, OHIO.

ROTARY GAME.

Application filed July 5, 1928. Serial No. 290,594.

This invention relates to an improved construction of rotary game.

The objects of this invention are to devise a rotary form of game which embodies several different games capable of being played upon convenient removal and reversal of certain parts; and to devise such an arrangement which, at the same time, is of comparatively simple and compact construction and which therefore can be manufactured and sold at comparatively low cost.

Other objects will appear from the following description and claims when considered together with the accompanying drawing.

Fig. 1 is a plan view; Fig. 2 is a view taken on line 2—2 of Fig. 1; and Fig. 3 is a view taken on line 3—3 of Fig. 2.

The box 1, which may be of circular, rectangular, or other suitable form, may be stamped out of metal and is provided with a centrally disposed upset portion 2 which is adapted to have permanently secured thereto the post 3. This post has its upper end pointed and is adapted to support for rotation thereupon the hollow shank portion 4 of the handle or spinner element. This spinner element has a shoulder portion 5 against which the disc 6 is adapted to abut and to be secured thereagainst by means of the nut 7 engaging the screw-threaded portion 8 on the shank 4. The knurled upper end portion 9 is adapted to be engaged by the fingers of the operator for spinning the disc which is supported and carried in the manner just now described. The disc 6 is provided with two different sets of characters upon each side thereof, each set of characters representing a certain form of game, as will appear from the drawing.

There is provided a cover 10 which has frictional engagement with the top portion of the box 1 and has an inwardly extending flange portion 11 which overhangs the marginal edge portion of the disc 6. The flange 11 serves as a means of protecting the edge portion of the disc and at the same time affords a convenient means of support for the arrow 12 which may be painted thereupon or stamped in the metal of the cover.

As will be seen from the drawing, the cover is readily removable from the box and the spinner element is also removable from the box 3 after the cover has been removed. The disc may be removed from the spinner element upon removal of the nut 7 and the disc may be reversed, with the result that either

side of the disc may be displayed so as to employ the games upon either side of the disc.

In using the game, the idea is to spin the disc and to employ either the outer or inner series of indications upon the one surface of the disc. For instance, as shown in Fig. 1, the outer series of indications represents a golf game, whereas the inner series refers to an airplane flight. The players will take turns in spinning the disc and will note which indication comes to position opposite the arrow 12, according to which of the two games is being played. Record will then be kept for each player of the different indications which come opposite the arrow, throughout the entire game.

Then when it is desired to play one of the other games on the reverse side of the disc, it is merely necessary to move the nut 7 and to follow the procedure above outlined. The outer series of indications on the reverse side of the disc are intended to represent the familiar game of roulette, while the inner series of indications may be understood to represent any other suitable form of game.

Thus, I have devised a game apparatus which is comparatively simple and compact in structure and which at the same time affords the possibility of playing any one of several different games by simply reversing the disc upon its supporting member. By means of the cover, as above described, the edge of the disc, which may be of cardboard or any other suitable material, is protected, and furthermore, the disc is prevented from unduly wobbling.

Because of the comparatively simple structure here involved, this amusement device may be manufactured and sold at comparatively low cost and at the same time, it is well adapted for attractive decoration. Another advantage consists in the fact that both the post and the cover therefor may be stamped out of metal, which furthermore serves toward the simplicity of construction and low cost of manufacture.

Further advantages will be obvious to one who is skilled in the art to which the present invention relates.

What I claim is:

An amusement device comprising a box, an upright post secured in the bottom of said box, a spinner means having a hollow shank portion rotatably and removably mounted upon said post, said spinner means having a shoulder and a screw-threaded portion, a cen-

trally apertured disk adapted to be engaged about the spinner means and to seat against said shoulder, a nut adapted to engage said screw-threads and to hold said disk in engagement with said shoulder, a series of indications on each side of said disk corresponding to as many different games, a removable cover for said box, said cover having an inwardly extending flange overhanging the

marginal portion of said disk, an indicator 10 provided upon the said flange for co-operation with said series of indications, whereby said disk may be reversed upon removal and adjustment of said removable parts, substantially as described

15

In testimony whereof, I hereby affix my signature.

OTTO J. HERMANN.
